ARTHUR J. SAVAGE, OF CHICOPEE FALLS, MASSACHUSETTS.

FIREARM.

935,237.

Specification of Letters Patent. Patented Sept. 28, 1909.

Application filed May 13, 1908. Serial No. 432,588.

To all whom it may concern:

Be it known that I, ARTHUR J. SAVAGE, of Chicopee Falls, in the county of Hampden and State of Massachusetts, have invented certain new and useful Improvements in Firearms; and I do hereby declare that the following is a full, clear, and exact description thereof, which will enable others skilled in the art to which it appertains to make and use the same, reference being had to the accompanying drawings, and to the characters of reference marked thereon, which form part of this specification.

The object of my present invention is to provide an automatically re-loading fire arm, which is simple in construction and efficient in operation.

Figure 1 shows a longitudinal vertical sectional view of the fire arm with the parts in the firing position. Fig. 2 shows a similar section with the parts in the open position. Figs. 3, 4 and 5 show details of the hammer and trigger in sundry positions. Fig. 6 is a detailed view partially in section of the inertia piece and its connecting or extension part. Fig. 7 is a cross section on line A—A of Fig. 6, showing particularly a handle for manually operating the breech block. Fig. 8 is a side elevation from the inside of the portion of the frame or receiver which attaches to the barrel, in connection with portions of the barrel and magazine, and in connection with the mechanism normally mounted on and separating with the barrel portion. Fig. 9 is a top or plan view of the breech block in connection with a portion of a cartridge shell shown in connection therewith. Fig. 10 is a section on line G—G of Fig. 8, through the barrel magazine, inertia piece and other parts. Fig. 11 is a section on line B—B of Fig. 8 through the barrel portion of the receiver or frame, the breech block and other connecting parts. Fig. 12 is a section on line D—D of Fig. 8 through the barrel portion of the frame. Fig. 13 is a section on line E—E of Fig. 15 through the stop portion of the frame, together with parts mounted thereon. Fig. 14 is a front or face end view of the breech block. Fig. 15 is an elevation from the inner side of the stock portion of the frame, together with the mechanism mounted on and separating with this part of the frame. Fig. 16 is an end view of the frame portion of the stock shown in Fig. 15, as seen from the right end of

Referring to the reference letters and figures in a more particular description, 20 indicates the barrel which is screw-threaded into the forward end of the barrel portion 60 21 of the frame, and 22 is the butt stock which is secured by means of tangs to the stock portion 23, of the frame or receiver. The barrel portion 21 of the frame consists in the main of a side wall 21^a and a top 65 plate 21^b, together with an enlarged or thickened end at the front, as indicated at 21^c, which receives the rear screw-threaded end of the barrel as well as the rear end of the tubular magazine 24 and against the front 70 face of which is fitted the rear end of the forestock 25. The stock portion of the frame consists in the main of a side wall 23^a, a bottom plate 23^b and a thickened wall at 23^c from which the tangs carrying the stock 75 extend and which affords a shoulder at 26 against which the rear end of the frame part 21 is adapted to fit. The forward end of the frame part 23 is provided with a socket at 27 adapted to receive a projection 80 28 provided on the part 21^c. This socket and projection at the front end in connection with the screw 29 toward the rear serves to secure the frame parts 21 and 23 together, and when secured together they 85 form a chamber to receive the operative mechanism of the fire arm or the major portion thereof.

The breech block 30 is arranged to reciprocate longitudinally with reference to the 90 barrel in the space immediately to the rear of the barrel under the top plate 21^b and confined between the side plates 21^a and 23^a. The rear end of the breech block is provided with a pin or roller 31, which is received in 95 and is movable along the longitudinally-arranged slot 32 provided in the frame wall 21^a. The forward end of the breech block is provided with a downwardly extending projection 30^a which contains the rearwardly 100 inclined cam slot 33. This slot receives the pin or projection 34 provided on the rear end of the extension or connecting bar 35 of the inertia piece 36. The inertia piece 36 is arranged under the barrel 20 and surrounds and slides along the magazine tube 105 24 and is housed within the forestock 25, which is suitably recessed to permit the reciprocating movement of the inertia piece. The inertia piece is moved toward its forward position and the breech block is operated and closed by the spring 37 coiled

about the tubular magazine which serves as a guide therefor and confined between the forward face of the part 21^a and the rear face of the inertia piece. The extension or connecting part 35 of the inertia piece is arranged to operate in a groove or slideway 38 in the inner face of the wall 21^a of the frame. This arrangement enables the projection 34 to be supported effectively. The breech block 30 is provided with a hook extractor 40 pivotally mounted and held in cartridge engaging position by a spring 41. The head of the cartridge as X is adapted to be gripped between the extractor 40 on the one side of the face of the breech block and the hooked flange 42 on the opposite side. The ejector 45 is mounted in a removable base plate 46 let into the wall 23^a of the frame, and the ejector is adapted to be received in, and allowed to come in engagement with the cartridge head by the provision of, the groove 47 in one side of the block. In the breech block is also mounted the firing pin 50, which extends longitudinally through the length of the block and is reduced at its forward end to operate through a small opening, as shown in Figs. 1 and 2, to engage a cartridge while it projects at the rear end to adapt it to be struck by the hammer. The spring 51 is provided, which serves to retract the firing pin.

The hammer 52 is pivotally mounted either directly on the frame holding screw 29, or on a sleeve surrounding this screw, and is adapted when the block is in closed position to strike the rear end of the firing pin as shown in Fig. 1. The hammer 52 is operated by a spring 53 coiled around a sliding or reciprocating stem 54, which, at one end, is provided with a conical head 55 affording a shoulder against which one end of the spring 54 bears, and a nose or point engaging in a socket in the lower end of the hammer 52. The forward end of the spindle 54 is arranged to slide freely in an opening provided in the front end of the part 23^a, and the spring and spindle are received in a recess or socket 56 in which they are well housed and still easily accessible and assembled or removed.

Pivoted mounted at 57 on the hammer 52 is the hammer pawl 58. The part 58 has only a limited swinging movement on the pivot 57 with reference to the hammer and is held to its open position by a spring 59. The part 58 provides a catch shoulder 61, while the hammer 52 provides a catch shoulder 60, either of which is adapted to be engaged by catch shoulders on the trigger 62, which trigger is pivoted in the frame at 63 and is operated to its direct hammer catching or holding position by the spring 64. The distance between the catch shoulders 60 and 61 is a trifle or somewhat greater than the distance between the catch shoulders on the trigger 62, which

are adapted respectively to engage these with. Slidely mounted in a socket 65 in the frame immediately at the rear of the trigger is the trigger safety catch 66 adapted to engage with and lock the trigger.

A passage 70 through the front wall 21^a of the frame is provided in line with the rear end of the tubular magazine and allows the passage of the cartridges onto the inclined loading platform 71 provided in the forward end of the frame part 23. To the rear of the loading platform is provided the cartridge stop 72 pivotally mounted on the receiver part 23 at 73. The cartridge stop is operated to its elevated or upper position, as shown in Figs. 1 and 15, by the spring 74, and is adapted to be depressed by the breech bolt engaging with projection 72^b. The cartridge stop has a cartridge engaging shoulder 72^a. The cartridges are fed back against the cartridge stop 72 by a magazine spring 75, together with a magazine follower 76.

On the inertia piece extension bar 35 there may be provided a knob or handle 80, by means of which the inertia piece and block may be manually operated, there being provided, of course, for a suitable distance a slot through the wall 21^a to permit the reciprocal movement of this knob in connection with the inertia piece.

It is obvious that the gun can be readily taken down by loosening the thumb-screw 29, when the parts of the frame are separable and the working parts of the fire arm made accessible and largely readily removed for cleaning, inspection or replacing of parts. The arm may also be readily put together and secured simply by operating the thumb-screw 29.

When properly assembled for use, the magazine may be loaded from the front end in any of the usual manners employed in connection with tubular magazines. The follower and follower spring will move the cartridges backwardly until the rearmost cartridge becomes caught on the cartridge stop shoulder 72^a. For the purpose of getting the gun into shooting condition, the operator will operate the breech block 30 once by means of drawing back on the knob 80. This movement compresses the recoil spring 37, slides back the breech block until it comes to a stop against the end of the slot 32 or the shoulder m on the frame, when the front end of the breech bolt is swung downwardly by the action of the pin or projection 34 in the cam slot 33. In its downward swinging movement the breech block first strikes the projection 72^b on the top of the cartridge stop 72. This depresses the cartridge stop sufficiently to throw the stop shoulder 72^a out of operative position, when the rearmost cartridge is immediately moved backwardly until it strikes the breech block. The continued swinging downward movement of the

front end of the block passes the hook flange 42 down one side of the head of the cartridge shell, while the extractor 40 engages with the opposite edge of the head and the cartridge is thus secured to the forward end of the breech block while resting on the loading platform 71. When the operator releases the knob, the spring 37 serves to first elevate the forward end of the breech block by reason of the incline cam slot 33, the breech block carrying with it projecting from the front end thereof the cartridge. Following the upward swinging movement of the forward end of the breech block the continued operation of the spring 37 then closes the breech block and introduces the cartridge into the cartridge chamber of the barrel. When the breech block is operated to open position as before described, the rear end rides over and cams down the hammer 52. In the first part of this movement the block runs on ways 90, which hold up the front end of the breech block until it has nearly reached the limit of its reciprocating movement. When the hammer is cammed down it is caught in cocked position by either the shoulder 60 on the hammer or the shoulder 61 of the hammer pawl 58 engaging with one of the two holding shoulders of the trigger 62, depending on whether the trigger is in one position or the other. If the trigger is in the rear position, it will catch and secure the hammer in cocked position by operating as shown in Fig. 4. If the trigger 35 is released by the operator, the spring 64 then moves it to its forward position, disengaging it from the shoulder 61 and the nose of the trigger engaging with the shoulder 60. If the trigger be now pulled, the nose engaging with the shoulder 60 will be released, the rear end of the trigger engaging with and elevating to some extent the rear end of the hammer pawl 58 in effecting the release. When released the hammer, of course, 40 will strike the firing pin and the explosion will take place in the cartridge. The recoil from the shell will blow back the block longitudinally, re-setting the hammer, which affords some resistance to the opening movement, and bringing along with it the inertia piece 36 and compressing the recoil spring 37, which furnishes additional resistance to the opening of the breech block.

Before the breech block has reached the limit of its rearward movement, the shell held by the extractor on the one side and engaging with the ejector on the other side is expelled through the opening 81 in the side of the frame. When the breech block has 45 reached the limit of its rearward movement at the shoulder 75 and the end of the slot 32, the continued rearward movement of the inertia piece 75 through its inertia operating through the medium of the incline slot 33 and the projection 34 engaging therein,

serves to swing down the forward end of the breech block, release the cartridge stop and engage with a cartridge on the loading platform. When the inertia of all the parts has been overcome, the spring 37 then comes into operation and moves the inertia piece forward, elevating the breech block and closing the same and passing the cartridge into the barrel as before described, at which time the fire arm is again ready for shooting by operating the trigger 62. The forward movement of the breech block is prevented until it has resumed its proper horizontal position by the front end of the block engaging with the shoulder 91 on the frame. This shoulder 70 terminates at the upper end at a point to allow the block to pass it when in correct longitudinal position.

The automatic re-loading above described takes place so rapidly that the operator is usually unable to release the trigger in time to again secure the hammer, and on this account the catch shoulder 61 is an important factor, in that it engages with the trigger when in normal tripped position to secure the hammer and provides for returning the trigger to its normal untripped position without releasing the hammer.

It is evident that many modifications and changes in and from the construction herein described may be made without departing from the invention described and intended to be covered by the claims.

What I claim as new and desire to secure by Letters Patent is:

1. The combination in a fire arm of a barrel, a frame, a longitudinally and vertically movable recoil operated breech block, an inertia piece connected to the breech block and serving to operate the breech block vertically, substantially as set forth.

2. The combination in a fire arm of a barrel, a frame, a recoil operated breech block mounted to reciprocate and swing in the frame, an inertia piece connected to the block for independent movement with reference to the block and arranged to operate the block in its swinging movement, substantially as set forth.

3. The combination in a fire arm of a barrel, a frame, a recoil operated breech block mounted to reciprocate and swing in the frame, an inertia piece connected to the block for independent movement with reference to the breech block and arranged to operate the block in its swinging movement, a recoil spring arranged to operate the inertia piece and breech block, substantially as set forth.

4. The combination in a fire arm of a frame, a magazine, a breech block, and block operating mechanism arranged to allow the block to reciprocate longitudinally and swing downwardly at its forward end when substantially at the limit of its rearward movement, a loading platform in the frame ar- 130

- rauged on an incline substantially conforming with the incline position of the block and onto which the magazine is arranged to deliver and arrange with reference to the rear- 45
 5 downwardly-swinging portion of the breech block to deliver the cartridges to the breech block, and a breech block, actuated, movable, cartridge stop at the rear of the loading platform, substantially as set forth.
- 16 5. The combination in a fire arm of a frame, a barrel, a magazine, a breech block having means for engaging and supporting a cartridge projecting from its face, and the breech block operating mechanism arranged 50
 15 to allow the block to reciprocate longitudinally and swing downwardly at its forward end when substantially at the limit of its opening movement, an incline loading platform in the frame onto which the magazine 55
 20 delivers cartridges and on which the cartridge engaging means of the block engages the cartridge, and a breech block actuated movable cartridge stop at the rear end of the platform, substantially as set forth.
- 25 6. The combination in a fire arm of a recoil operated breech block sliding and swinging in the frame and having an inclined cam slot, and an inertia piece relatively movable with reference to the breech block and 60
 30 connected with the breech block in said inclined slot, and a re-action spring, substantially as set forth.
7. The combination in a fire arm of a barrel and frame, a recoil operated breech block 65
 35 mounted for longitudinal and swinging movement in the frame and having an inclined cam and a firing pin mounted therein, an inertia piece connected to said breech block for relative movement in said cam, a
 40 recoil spring, and a spring pressed hammer operating in connection with the firing pin and breech block, substantially as set forth.
8. The combination in a fire arm of a bar- 70
 rel and a frame, a breech block mounted in the frame for reciprocating and swinging movement at its forward end, means on the breech block for engaging and holding the cartridge projecting from the forward face thereof, a cartridge loading platform in the frame in connection with which the breech block is adapted to operate, a cartridge stop at the rear of the loading platform and arranged to be released by breech block, and a magazine supplying cartridges onto the loading platform, substantially as set forth. 75
 9. The combination in a fire arm of a barrel and frame, a breech block mounted in the frame for reciprocating and swinging movement at its forward end, means on the forward end of the breech block for securing 80
 60 and supporting the cartridge projecting therefrom, a cartridge loading platform, a movable cartridge stop arranged to be operated by the breech block, and a magazine supplying cartridges onto the loading platform, substantially as set forth. 85
 10. The combination in a fire arm of a hammer, a hammer pawl hinged to the hammer, a spring for operating the hammer, a trigger having two catch shoulders adapted 90
 70 to engage with the hammer and hammer pawl respectively, and a spring for operating the trigger, substantially as set forth.
11. In a fire arm, the combination of a hammer having a catch shoulder, a hammer 95
 75 pawl, a trigger having two catch shoulders coöperating with the hammer shoulder and the pawl respectively, substantially as set forth.

In witness whereof, I have affixed my signature, in presence of two witnesses, this 11 day of May 1908.

ARTHUR J. SAVAGE.
